UNITED STATES PATENT OFFICE.

WALTER R. SCHLAGE, OF SAN FRANCISCO, CALIFORNIA.

DOOR-LATCH BOLT.

Application filed August 2, 1923. Serial No. 655,220.

This invention relates to a door latch and especially to a structure which permits the latch and its actuating plate to be assembled and formed of pressed or die-cut metal.

5 The object of the present invention is to generally improve and simplify the construction of devices of the character described, and especially to provide a latch and an actuating plate which are constructed 10 of sheet metal and adapted to be cut, formed and assembled by die action.

One form which my invention may assume is exemplified in the following description and illustrated in the accompanying 15 drawings, in which—

Fig. 1 is a plan view of a blank from which the actuating plate is formed.

Fig. 2 is a perspective view of the actuating plate showing the side flanges bent 20 to form the head portion.

Fig. 3 is a perspective view of the latch shell.

Fig. 4 is a central longitudinal section through the latch and its actuating plate.

25 Fig. 5 is a side elevation of the latch and its actuating plate.

Referring to the drawings in detail, and particularly to Figs. 1, 2 and 3, A indicates a door latch actuating plate, 2 a pair of 30 rearwardly projecting lugs, which are engaged by the retracted mechanism of the lock, and 3 a pair of side flanges which are bent upwardly to form an inner head member generally indicated at B. The actuating 35 plate, together with the retracting lugs 2 and the head member B, is formed from a metal blank such as shown in Fig. 1; this blank being cut from sheet metal by means of a blanking die. After the blank has 40 been formed it is subjected to a second die operation and during this operation the side wings indicated at 3 in Fig. 1 are bent up to form the head member B shown in Fig. 2. The plate A is at the same time slightly 45 offset as indicated at 4 to bring the plate in alignment with the retractive mechanism of the lock. By referring to Figs. 1 and 2, it will be noted that the forward ends of the wings 3 are cut on an angle as shown at 9. 50 This is of considerable importance as this angle produces an inclined face when the head member B is formed.

The latch proper is also constructed of sheet metal, a blank being first formed which 55 in turn is subjected to a set of drawing dies, these dies forming a shell-like member such

as shown in Fig. 3. The shell consists of a rounded portion 5, a flattened side face 6, and an end or bottom section which is arcuated or inclined as indicated at 7. The 60 shell when formed is slipped over the head member B. The inner edge of the shell is then seamed or flanged as indicated at 8, thereby securing the shell with relation to the head member B; the operation of blanking, forming and assembling the respective parts forming the actuating plate and the latch being thus completed. The object of cutting the wings 3 on an angle as indicated at 9 to form a forwardly inclined face on 70 the head member B is important as it produces a shape identical to the shell shown in Fig. 3. The flattened side of the shell 6 engages the lower side of the plate, the rounded portion 5 encloses the side wings 75 3, and the inclined end 7 of the shell engages the inclined face or angularly cut side wings shown at 9. A complete guide and support for the shell are thus formed and it is at the same time substantially reinforced so as to withstand the usual blows 80 encountered when in use.

An actuating plate and latch constructed and assembled in the manner described are not only cheap to manufacture but they also 85 reduce weight and increase the strength of the same; that is, it is well known that metal parts cut and shaped by die action are much tougher and stronger than articles of this character which are cast; castings being as 90 a rule too brittle and subject to breakage, particularly if the metal is fairly thin. Such a metal as brass, however, may be used to advantage where castings of this character are employed as it is not as brittle as cast- 95 iron or the like, but it increases cost and it does not produce a light weight structure such as illustrated in this application. For instance, the actuating plate indicated at A, together with the retractive lugs 2 and the 100 head member B, may be formed of ordinary cold rolled steel, black iron or heavy sheet metal. The latch shell shown in Fig. 3 may also be drawn from similar metal, for instance, soft steel, but if an attractive article or a high-grade product is desired, the shell is drawn from brass, thus one part of the latch mechanism may be constructed of one metal and the other part of another metal. 105 A variety of grades and products may thus be obtained without changing the construction or design, and a light weight product 110

may at the same time be produced without detracting from its strength or other qualities, and furthermore eliminating all necessity of machining any of the parts.

5 While the invention specified is more or less specifically illustrated, I wish it understood that various changes in form and proportion may be resorted to within the scope of the appended claims; similarly, that the 10 materials and finish of the several parts employed may be such as the experience and judgment of the manufacturer may dictate or various uses may demand.

Having thus described my invention, what 15 I claim and desire to secure by Letters Patent is:—

1. A device of the character described comprising a flat plate provided with a latch carrying end and an actuating end, a 20 pair of side wings formed on the latch carrying end, said wings being bent upwardly to join each other and rounded to form a latch carrying head, an offset formed in the plate back of said head, and a shell-shaped latch

adapted to be received by the plate and the 25 wings forming the head and completely enclosing the same, the inner end of said shell being seamed over the offset portion of the plate and the ends of the wings forming the head to secure the shell against endwise removal.

2. A device of the character described comprising a plate, a pair of retracting lugs formed on one end thereof and parallel with the plate, a pair of side wings formed on the opposite end, said wings being bent upwardly to join each other and rounded to form a head member, said wings presenting an inclined forward surface, an offset in the plate back of the wings and a shell like 40 latch carried by the head member and completely enclosing the same, said latch presenting an inclined face at its forward end and having its opposite end seamed over the side wings of the head and the offset portion 45 to secure the shell against endwise removal.

WALTER R. SCHLAGE.
